DESIGN FOR A GAME BOARD

Henry I. Hagloch, Canton, and Leo W. Rose, Sr.,
Dover, Ohio

Application June 12, 1945, Serial No. 120,041

Term of patent 7 years

(Cl. D34—5)

To all whom it may concern:

Be it known that we, Henry I. Hagloch and Leo W. Rose, Sr., citizens of the United States, residing at Canton, in the county of Stark and State of Ohio, and at Dover, in the county of Tuscarawas and State of Ohio, respectively, have invented a new, original, and ornamental Design for Game Board, of which the following is a specification, reference being had to the accompanying drawing, forming part thereof.

The single figure is a plan view of a game board, showing the new design. The article is of conventional thickness.

The lining shown on the drawing is used to denote the colors green, pink or red, yellow, and blue.

We claim:

The ornamental design for a game board, substantially as shown and described.

HENRY I. HAGLOCH.
LEO W. ROSE, SR.
